UNITED STATES PATENT OFFICE.

CECIL McCOBB BILLINGS, OF BROOKLYN, NEW YORK, ASSIGNOR TO DELMORE MANUFACTURING CO., INC., OF NEW YORK, N. Y., A CORPORATION OF NEW YORK.

DESIGN FOR A MOTOR-VEHICLE.

54,368.

Specification for Design.

Patented Feb. 10, 1920.

Application filed July 29, 1919. Serial No. 314,140. Term of patent 14 years.

To all whom it may concern:

Be it known that I, CECIL M. BILLINGS, a citizen of the United States, residing in the borough of Brooklyn, county of Kings, and State of New York, have invented a new, original, and ornamental Design for Motor-Vehicles, as illustrated in the accompanying drawing.

The figure presents a perspective view of a motor vehicle, showing my new design.

The ornamental design for a motor vehicle, as shown.

CECIL McCOBB BILLINGS.
